ACOUSTIC COUPLER

Virgil H. Johnson, Churubusco, Ind., assignor to Minnesota Mining and Manufacturing Company

Filed Apr. 7, 1972, Ser. No. 242,271

Term of patent 14 years

Int. Cl. D14—03

U.S. Cl. D26—14 A

FIG. 1

FIG. 2

FIG. 3

FIG. 4

FIG. 5

FIG. 1 is a top perspective view of an acoustic coupler showing my new design;

FIG. 2 is an end view thereof with the other end being substantially the same configuration;

FIG. 3 is a top plan view thereof;

FIG. 4 is a front view thereof; and

FIG. 5 is a rear view thereof.

I claim:

The ornamental design for an acoustic coupler, substantially as shown and described.
